KNITTING METHOD

Jean Lamont Stemm, New York, N. Y., assignor
to Wm. H. Horstmann Company, Philadelphia,
Pa., a corporation of Pennsylvania

Original application April 2, 1937, Serial No.
134,631. Divided and this application March
30, 1938, Serial No. 199,009.

3 Claims.

(Cl. 66—1)

This invention relates to a knitting gauge pattern adapted for the forming of tubular and other-shaped garments by knitting, crocheting, etc. This is a division of my co-pending application, Serial No. 134,631, for Knitting gauge pattern, filed April 2, 1937.

It is a well-known practice to provide patterns for the forming of garments from various types of fabrics. Also, patterns have been developed for forming the peripheral line of crocheted garments. All of such prior patterns, however, have delineated only the outer peripheral edge of the piece to be fitted into the garment. The use of seams compensated for slight errors.

In knitting, and particularly in knitting tubular garments, there are new problems which such prior patterns do not solve and which render them of very little value. In the first place, the tubular knitted garment affords no seams by which irregularities in knitting can be overcome. The irregularities are inevitable, yet the only course under such prior patterns is for the knitter to rip out a portion of the knitting when it is not true to the pattern line and reknit.

In the art of knitting, it is not so much the making of stitches which is difficult, it is the error which creeps in in following changes of pattern and changes of stitches as well as failure to follow the number of rows, etc. which the pattern calls for. In the making of hand-knitted garments, variance is always present due to different tension of the yarns used by different knitters and, in fact, by the same knitter at different times. Also, changes of yarn, needles, etc. often produce a difference in the knitting.

I have discovered that by utilizing the stretch allowance of a knitted garment in blocking that even though errors are made and even though the knitting is irregular within certain limits, a uniform and form-fitting garment can be produced while at the same time requiring very little ripping out and reknitting.

In the single figure of the drawing is shown a sheet A upon which appears a dotted line 10 indicating the line to which the skirt is knitted. As the knitting progresses, the skirt or other garment can be placed upon the pattern and if the peripheral edges coincide with the line 10, the knitter will know that the garment is of the proper size. As before stated, however, it is practically impossible for the ordinary knitter to bring the periphery of the skirt constantly in line with dotted line 10 because of the above-mentioned irregularities in knitting. Should the skirt be substantially wider than the area enclosed by the

dotted lines 10, the knitter would be confronted immediately with the question as to whether the knitting should be ripped out and reknitted. I have found that such irregularities can be taken care of completely by the use of a blocking stretch line indicated by the numeral 11. In blocking, the goods can be stretched a certain distance without affecting the appearance of the garment, and I utilize this stretch allowance to bring the outer periphery of the garment into a continuous, uniform or form-fitting line 11.

After the knitting is completed, the garment is placed upon the pattern, as illustrated in the drawing, and the folded edge or periphery of the skirt is pinned to the outer black line 11. The garment will stretch sufficiently to allow this to be readily accomplished. A hot iron is then used as in the usual manner to firmly block the skirt, with the result that the completed skirt is uniform in size and contour and the stitches 20 therein are of substantially uniform size. Thus all the irregularities which formerly appeared causing the edges of the skirt to form a waved line extending between the dotted line 10 and blocking line 11 now disappear and the contour 23 of the skirt is now even and uniform.

What has been accomplished by the blocking stretch allowance, as just described, can as readily be accomplished by the shrink allowance line. In other words, should it be desired to shrink the 30 knitted garment to a definite contour, as indicated by the dot and dash line 12, all the irregularities between the lines 10 and 12 can be readily taken up when the edge of the garment is pinned to the dot and dash line 12 and a hot iron is used 35 to set or block the garment.

Instructions as to the number of stitches, etc. appear on the sheet at exactly the points where the changes occur. In other words, some of the instructions will be spaced closely apart while 40 others will be spaced widely apart, depending upon the contour of the garment. A scale extends through the longitudinal center of the pattern.

In the operation of the device, the knitter follows the instructions which appear on the pattern itself and which indicate the changes in stitches, etc. as the knitting progresses. As the waved or irregular knitting line is formed, the knitter can by placing the garment upon the pattern observe whether the irregularities are 50 such as can be corrected by blocking. Should the irregularities exceed the limits, the knitting at that particular point can be ripped out and reknit. Should the irregularities be within the blocking or shrinking allowance lines, the knitter 55

will know that such irregularities can be readily corrected in the blocking or shrinking operations and that there is no need for ripping out and reknitting in such instances. By this means, it 5 is possible for a knitter to form a garment with much greater speed and with much less reknitting while at the same time being always certain that the final product will be uniform and even in contour and without excessive stretching of 10 the stitches.

10 The gauge pattern is simple, easy to follow, and renders a tremendous saving in time and effort and results in much greater certainty than heretofore attained with prior patterns.

15 Summarizing, in the improved method of forming a hand knitted garment, I first knit the garment to bring the peripheral edges thereof within the two pattern lines on the paper sheet when the garment is placed on the sheet, then I 20 treat the material after the knitting is completed so as to cause it to conform to one of the lines. Such treating may be in the nature of stretching the garment after the knitting is complete and pinning the periphery of the garment to one 25 of the lines, and then ironing or otherwise setting the garment in this position.

30 The invention is particularly useful in connection with knitting and crocheting, although it obviously may be applicable to other uses and it will be understood that the use of the word "knitting", as used in the appended claims, is in 35 its broad sense, including crocheting, etc., as well as what is known specifically as knitting.

35 In the drawing, the points where changes in the stitches occur are indicated by a number of crosses extending in spaced relation adjacent the dotted knitting line 10. In alignment with two of the crosses are work instructions. The work 40 instructions which normally appear in line with the other crosses have been omitted from the drawing for the purpose of clarity.

The foregoing detailed description has been given for clearness of understanding only, and no unnecessary limitations should be understood therefrom, but the appended claims should be construed as broadly as permissible, in view of 5 the prior art.

I claim:

1. A method of forming a hand-knitted garment, comprising: knitting the garment to bring the periphery thereof within pattern lines on a 10 paper sheet when the garment is placed thereon, the stretch allowance for said knitted garment being defined by the space between said lines, and treating the material after the knitting is completed to cause the material to conform to 15 one of the lines.

2. A method of forming a hand-knitted garment, comprising: knitting the garment to bring the periphery thereof within two pattern lines on a paper sheet when the garment is placed 20 thereon, the space between said lines defining the stretch allowance of the knitted garment, stretching the garment after the knitting is completed and pinning the periphery thereof to the outermost of said lines, and then ironing the garment 25 in this position.

3. A method of forming a hand-knitted garment, comprising: providing a flexible sheet larger than the garment to be knitted with at least two garment pattern lines spaced from 30 each other, the space between the lines defining substantially the stretch allowance of the knitted garment, knitting the garment to bring the periphery thereof when applied to said flexible sheet within the said spaced lines, stretching the 35 garment after knitting and securing the periphery thereof to the outermost of said lines, and treating the material to cause it to conform to said outermost line.

40 JEAN LAMONT STEMM.
